UNITED STATES PATENT OFFICE.

JULIUS M. GOLDSTEIN, OF ONEIDA, NEW YORK.

DESIGN FOR A WHEEL-RIM.

SPECIFICATION forming part of Design No. 26,116, dated September 29, 1896.

Application filed May 18, 1896. Serial No. 592,058. Term of patent 7 years.

To all whom it may concern:

Be it known that I, JULIUS M. GOLDSTEIN, a citizen of the United States, residing at Oneida, in the county of Madison and State of New York, have invented and produced a new and original Design for Wheel-Rims, of which the following is a specification, reference being had to the accompanying drawings, showing a part thereof.

My invention will be understood by reference to the accompanying drawings, in which the same numbers refer to corresponding parts in all the views.

Figure I is an elevation of a portion of a wheel having a rim of my original design. Fig. II is an enlarged section of said wheel-rim. Fig. III is a similar enlarged view showing a portion of the side of the wheel-rim in perspective.

The wheel-rim consists of three members, numbered, respectively, 1, 2, and 3, the outer edge of the inner member 1 being marked by the lines 4 4. This member has substantially

flat sides 5 5 and an inner straight or flattened face 6 and rounded corners 7 7. The 25 middle member 2 begins at the line 4 and extends thence with swelling or convex sides 8 8 to the lines 9 9. The outer member 3 extends from said line 9 9 with convex or swelling sides 10 10, which meet in the rounded 30 point 11, so that it resembles in outline the section of one end of an egg.

Having thus fully described my invention, what I claim, and desire to protect by Letters Patent, is—

The design for a wheel-rim substantially as herein shown and described.

In witness whereof I have hereunto set my hand, in the presence of two attesting witnesses, at Oneida, in the county of Madison, 40 in the State of New York, this 4th day of May, 1896.

JULIUS M. GOLDSTEIN.
